UNITED STATES PATENT OFFICE.

JOSEPH HARRISON, OF TUNSTALL, STOKE-ON-TRENT, ENGLAND.

DESIGN FOR A VEGETABLE DISH OR SIMILAR ARTICLE.

Application filed March 4, 1927. Serial No. 20,965. Term of patent 3½ years.

To all whom it may concern:

Be it known that I, JOSEPH HARRISON, a subject of the King of Great Britain and Ireland, and resident of Tunstall, Stoke-on-Trent, in the county of Stafford, England, have invented a new, original, and ornamental Design for a Vegetable Dish or Similar Article, of which the following is a specification, reference being had to the accompany drawing, forming part thereof.

I claim:

The ornamental design for a vegetable dish or similar article, as shown.

JOSEPH HARRISON.
